[57] CLAIM

The ornamental design for a holder for crayons, markers, pencils and the like, as shown and described.

DESCRIPTION

FIG. 1 is a top plan view of a holder for crayons, markers, pencils and the like showing my new design;

FIG. 2 is a side elevational view, all other sides being identical thereto;

FIG. 3 is a bottom plan view; and,

FIG. 4 is a bottom perspective view thereof.

FIG-4
